The ornamental design for a cycling shoe insole, as shown and described.

DESCRIPTION

FIG. 1 is a top perspective view of the cycling shoe insole, showing my new design;

FIG. 2 is a top plan view of the invention illustrated in FIG. 1;
FIG. 3 is a bottom plan view of the invention illustrated in FIG. 1;

FIG. 4 is a right side view of the invention illustrated in FIG. 1;

FIG. 5 is a left side view of the invention illustrated in FIG. 1;
FIG. 6 is a front view of the invention illustrated in FIG. 1; and,

FIG. 7 is back view of the invention illustrated in FIG. 1.
